UNITED STATES PATENT OFFICE.

JOHN BURT, OF HEBBURN, ENGLAND.

APPARATUS FOR RAISING AND LOWERING SHIPS' BOATS.

No. 800,841.

Specification of Letters Patent.

Patented Oct. 3, 1905.

Application filed February 9, 1904. Serial No. 192,790.

To all whom it may concern:

Be it known that I, JOHN BURT, a subject of the King of Great Britain and Ireland, residing at, and whose post-office address is, 27 Wreigh 5 street, Hebburn-on-Tyne, in the county of Durham, England, have invented certain new and useful Improvements in Apparatus for Raising and Lowering Ships' Boats, (for which I have applied for a patent in Great Britain under No. 6,945, dated March 25, 1903, and in Germany under date January, 1904,) of which the following is a specification.

This invention relates to apparatus for raising and lowering ships' boats, and has for its 15 object to provide means whereby ships' boats can be expeditiously launched and maintained in a perfectly horizontal or level position during lowering or raising.

The davit-arms of the apparatus are pivoted 20 at their lower ends to the side of the vessel, and the boat rests in chocks or cradles that are formed on or secured to a horizontal stay-bar pivoted in the free or upper ends of the davit-arms. The stay-bar is provided with a bell- 25 crank or equivalent device to which the raising and lowering tackle and one end of a supplementary arm or jib are connected, the other end of said arm or jib being pivoted to the side of the vessel at a point below the level of 30 the hinges of the davit-arms.

By way of example I will now proceed to describe one way of carrying my invention into effect, reference being had to the accompanying drawings, wherein--

35 Figure 1 is a part cross-section showing a boat in the inboard or housed position. Fig. 2 is a side elevation of Fig. 1; and Figs. 3 and 4 are similar views to Fig. 1, showing the boat in different outboard or swung-out positions.

40 Referring to the drawings, *a a* are the davits, the lower ends of which are hinged at a suitable distance apart to the side of the vessel, as at *b b*. The boat *c* rests in chocks or cradles *d d*, formed on or secured to a horizontal stay-bar *e*, which is revolubly mounted 45 in eyes *f f* in the free ends of the davits *a a*. Normally the chocks *d d* rest on blocks *g g*, disposed on the deck or on a platform *h*, supported from the deck. The stay-bar *e* is formed 50 or provided at its center or in other suitable position with arms *j k*, which constitute a bell-crank or equivalent device. To the arm *j*

is attached one end of a supplementary arm or jib *m* of the same length as the davit-arms *a a*, and the said arm *j* is provided with a stop 55 or projection *n* to coat therewith when the parts are in the position shown in Fig. 1 for the purpose of keeping the boat steady. The other end of the supplementary arm or jib *m* is hinged to the side of the vessel at a point 60 below the hinges *b b* of the davits *a a*, as at *o*. The raising and lowering tackle is connected to the bell-crank arm *k* and may conveniently consist of a rope passing under and over rollers in a bracket *p*, disposed on the platform 65 *h*, and through tackle-blocks *q r*, connected, respectively, to the arm *k* and to a loop *s*, provided on the platform *h*.

When it is desired to lower the boat after the usual lashings have been undone, the davits *a a* are swung outward, as shown in Fig. 3, carrying the boat supported on the chocks or cradles *d d* with them, and the arm or jib *m*, coacting with the arm *j* on the bar *e*, maintains the chocks or cradles, and consequently 75 the boat, in a level or horizontal position until the latter is water-borne, as shown in Fig. 4, when on the davits *a a* being still farther lowered the boat can float clear of the chocks *d d* and the davits can be returned inboard. 80

What I claim as my invention, and desire to secure by Letters Patent, is--

1. In apparatus for raising and lowering ships' boats, davit-arms pivoted at their lower ends to the side of the vessel, a horizontal stay-bar pivoted to the free upper ends of the davit-arms, cradles secured to said horizontal stay-bar and adapted to receive the boat, a supplementary arm pivoted to the side of the vessel at a point below the level of the hinges 90 of the davit-arms, a bell-crank lever mounted on the stay-bar and adapted to rock therewith, one arm of said lever being pinned to the free upper end of the supplementary arm and the other arm being adapted to be secured 95 to raising and lowering tackle.

2. In apparatus for raising and lowering ships' boats, davit-arms hinged to the side of the vessel below the level of the boat when in its inboard position, a supplementary arm of the same length as the davit-arms hinged to the side of the vessel at a point below the level of the hinges of the davit-arms, chocks mounted on a stay-bar pivoted to the free

ends of the davit-arms, a bell-crank lever provided on the stay-bar and having one arm pivoted to the upper end of the supplementary arm and the other arm being adapted to be
5 secured to raising and lowering tackle; substantially as and for the purposes set forth.

In witness whereof I have hereunto signed

my name in the presence of two subscribing witnesses.

JOHN BURT.
